Harry Jacobson
ATTORNEY

UNITED STATES PATENT OFFICE

THOMAS A. GIBSON, OF BROOKLYN, NEW YORK

SPRING TOGGLE TABLE ADJUSTMENT FOR WIRE STITCHING MACHINES

Application filed December 27, 1930. Serial No. 505,098.

This invention relates to the work supporting members of machines such as wire stitching and the like machines, and contemplates, among other things, the provision of a yieldable work support so designed as to avoid danger of damage to the machine when work, of greater thickness than that to which the machine is adjusted, is operated upon.

In wire stitching machines heretofore in general use, and to which my invention is particularly applicable, the work supporting table or arm is unyieldable and rigid though capable of adjustment to the proper height to receive and support an article of work, such as a stack of sheets of certain thicknesses, within the limits of the machine. Should the operator, therefore, attempt to stitch through a stack of paper or the like, of greater thickness than that to which the machine has been adjusted, serious damage frequently occurs. Furthermore, in such machines, after the work table or support has been adjusted to receive work of the maximum thickness which the machine can operate upon, work of greater than the maximum thickness cannot be operated upon at all. Should the operator inadvertently attempt to stitch a stack of sheets of greater thickness than the adjustment of the work support warrants, or of greater than the maximum thickness which the machine will properly take, the machine will become damaged or broken, as above mentioned, or else, at best, the pre-formed staples will not be of sufficient length to pierce the work, so that the stack cannot be properly stitched.

My invention eliminates these difficulties, and makes it possible to operate upon a stack of substantially double the thickness of that to which the machine has been adjusted. A stack of such greater thickness may be stitched by driving the staples into the stack as far as they will go, from one face of the stack, without clinching them, and then turning the stack over and driving the staples through from the other face of the stack.

By the use of my invention, the insertion of stacks of greater thickness than that to which the machine has been adjusted, can-

not damage the machine or jam it, or have any other undesirable results.

The various objects of my invention will be clear from the description which follows, and from the drawing, in which,

Fig. 1 is a front elevation of one form of my new work support adjusting mechanism as applied to a wire stitching machine which is provided with a table for receiving a stack of sheets.

Fig. 2 is a side elevation of the same, and

Fig. 3 is a side elevation of a somewhat modified form of my invention.

In that practical embodiment of my invention which I have illustrated by way of example, I have shown my new work support adjusting mechanism applied to a wire stitching machine, though it will be understood that it need not necessarily be limited to such machines. The front block 10 of the usual type provided in wire stitching machines carries the staple guide slide 11, and the slidable staple driver 12. Since these parts are well known in the art, and since the mechanism for operating the same is also well known, no further description thereof is deemed necessary. The staple supporter 13, which is alternately projected and retracted, is similarly of well known construction and need not be further described. As illustrated, the work supporting member may include a table designated generally by the numeral 14, below which is a supporting cross bar 15, to which the table is adjustably secured as by means of the adjusting screws 16.

It will be understood, however, that for the parts 14, 15 and 16 may be substituted, an arm extending from the main frame 17 in a manner which is well known.

In any case, the work supporting member is preferably mounted for vertical movement relatively to the bearing 18, being provided with a depending part such as the shaft 19, passing through and slidable in said bearing. At its lowermost end, the shaft 19 terminates preferably in an enlarged part, such as the gage carrier 20. The gage 21 is secured in a suitable groove in the gage carrier, and slides in the groove 23 of the bear-

ing 18, when said bearing and the gage carrier 20 are moved relatively.

The gage 21 is further suitably graduated as by the markings 22, to measure or indicate the distance between the upper surface 25 of the gage carrier and the under surface 24 of the bearing 18. The gage therefore serves to indicate the adjustment necessary to cause the machine to draw the proper length of wire to form a staple of the proper size. The clincher box 26 is secured to the shaft 19 and moves therewith and with the carrier 20, when the pressure on the work support exceeds the normal amount necessary to drive a staple into and through a stack, to the thickness of which the machine has been adjusted. This happens when the stack is of greater than the predetermined thickness to which the machine has been adjusted. The staple clinching mechanism in the clinching box 26 is of the usual type and need not be shown or described.

The distance between the top of the work table 14 and the lower end of the staple guide 25 slide 11, when the slide is in its lowermost position, (on the stack), is normally the same as the distance between the surfaces 24 and 25, said distance being determined by the reading on the gage 21.

In order to adjust said distance to the thickness of the stack to be operated upon, a four-arm toggle adjustment is provided. Said toggle is preferably interposed between the bearing 18 and the gage carrier 20.

The upper toggle members or arms 27 and 28 are hinged together and pivoted to the bearing 18 in the usual manner, as by means of the pivot bolt 29, while the lower toggle members or arms 30 and 31 are pivoted to the toggle block 32. The lower surface 33 of the block 32 normally rests upon and engages the upper surface of the lug 34 extending from the gage carrier 20, but is not otherwise connected thereto, so that the lug may move downwardly independently of the movement, if any, of the block.

As shown in Figs. 1 and 2, the spring-carrying pin 35 extends from the block 32, and serves to maintain the compression spring 38 in place. Said spring is interposed between the adjusting nut 36 and the under surface of the lug 34. Threads are provided at the lower end of the pin 35, engaging the corresponding threads on the adjusting nut for the purpose of adjusting the spring pressure. A suitable washer as 39 may be inserted, if desired, between either end of the spring and the member or part against which it presses. It will be seen that by turning the nut 36 along the member 32, in either direction, adjustment of the pressure upon the spring 38 may be obtained to increase or decrease the force exerted by the spring and consequently, to increase or decrease the resistance of the work support to movement under the pres-

sure exerted on the support during the staple driving operation.

For adjusting the effective distance between the upper and lower ends of the toggle connection, and thereby adjusting the distance between the surfaces 24 and 25, the lower ends of the upper toggle arms 27 and the upper ends of the lower arms 30 are hinged together by means of the pin 46. Similarly, the toggle members 28 and 31 are hinged together by means of a similar pin 47. Said pins 46 and 47 are threaded to receive the adjusting screw 48.

It will be understood that on rotation of the screw 48 in the proper direction, the pins 46 and 47 are separated or drawn together, as may be desired. When separated, the block 32 presses against the lug 34 and moves said lug, together with the carrier 20, the shaft 19 and the table 14 downwardly, thereby decreasing the height of the table 14. When the ends of the toggle are drawn together, the block 32 tends to rise up off the lug 34, but the spring 38 presses them together, and thereby normally maintains the work support in proper adjusted position.

In the normal operation of the machine, it is intended that the operator use a stack of sheets, the thickness of which is substantially that of the distance between the surfaces 24 and 25 indicated on the gage 21. Should it be desired, however, to stitch a stack of greater thickness, or should such a stack be inadvertently inserted into the machine, no damage can result. The driver 12, in driving the staple into such a stack, may safely complete its full normal stroke. Should the stack be of such greater thickness, the final part of the stroke of the driver, instead of jamming the parts or damaging the machine, will exert its pressure upon the table 14 and therethrough on the shaft 19 and the gage carrier 20. The undue force thus exerted, results in downward movement of the shaft 19 and the parts carried thereby against the action of the spring 38.

It will be understood that by regulating the force exerted by the spring, the point at which downward movement of the work support begins, can be accurately determined. The table 14 therefore yields downwardly under the excessive force due to excess thickness of the work, or to failure to adjust the work support to such thickness. The spring 38 returns the parts to their normal positions on the release of the pressure as when the driver 12 moves upwardly on its return stroke.

It will be seen that during normal adjustment of the table 14 by means of the adjusting screw 48 as when the table height is decreased, the spring 38 further serves to maintain the lug 34 in contact with the lower surface 33 of the toggle block 32.

In that form of my invention illustrated in

Fig. 3, an extension 50 projecting from the main frame 17 of the machine receives the downward pressure of the spring 38. Said extension is suitably apertured as at 51 to receive the adjusting nut 52. Preferably held on said nut by the pressure of the spring, is the member 53, provided with an annular recess 54 for the reception of the end of the spring, and with the upstanding pin 55 arranged inside of the spring and maintaining it in position. At its lower end, as 56, the nut 52 is threaded into the threaded aperture 51 of the extension 50. The upper end of the spring 38 may, if desired, be inserted into a suitable recess in the lower surface of the carrier 20. On downward movement of the shaft 19 under excess pressure of the driver 12, as in the cases previously described, the resulting downward movement of the carrier 20 compresses the spring 38 and takes up the excess portion of the stroke. The spring 38 returns the parts to their normal positions, as has been previously described.

It will be seen that I have provided a simple and efficient yieldable and adjustable work support for machines of the character described; that by means of my invention, the dangers inherent in rigid supports are eliminated, that stacks of much greater thickness than the maximum possible adjustment of the machine may be operated upon therein; that such stacks may be stitched by driving staples through each of the faces of the stack without clinching; and that I have provided an effective mechanism designed to avoid the dangers inherent in rigid work supports and to meet the severe requirements of practical use.

While I have shown and described certain specific embodiments of my invention, I do not wish to be understood as limiting myself thereto, but intend to claim my invention as broadly as may be permitted by the state of the prior art and the terms of the appended claims.

I claim:

1. In a wire stitching machine, a work support adapted to support a pile of paper sheets, means for stapling said sheets, a shaft depending vertically from the support, a frame provided with a bearing sleeve for the passage of said shaft, an enlarged member secured to the shaft below said bearing, a stop above and in the path of the enlarged member, means supported by the frame and connecting the stop to the frame for adjusting the height of said stop and thereby determining the uppermost position of said table, and a compression spring arranged below and in the path of said enlarged member and adapted to be compressed on the downward movement of the table, the shaft and the member as a unit.
2. In a wire stitching machine, a work support adapted to support a pile of paper

sheets, means for stapling said sheets, a frame carrying said support, a stop adjustably secured to the frame, means including a threaded member for adjusting the effective height of said stop relatively to the frame, a member on the shaft below said stop, a spring below said member normally urging the member upwardly into engagement with said stop and thereby determining the uppermost position of the table, and a threaded member mounted independently of the adjusting means for adjusting the force exerted by the spring.

3. In a wire stitching machine, a work supporting member, stapling means, a gage adapted to indicate the height of the member, means for adjusting the effective height of said member to support an article of predetermined thickness, and a compression spring mounted independently of the adjusting means normally maintaining the member in its adjusted position and yieldable with said member on the operation by the machine upon an article of greater thickness.

4. In a machine of the character described, a frame, an upright bearing on the frame, a shaft slidable in the bearing, a work supporting table at the upper end of the shaft, a gage carrier at the lower end of the shaft, an adjustable toggle connection pivoted to the bearing and abutting loosely against the gage carrier, and a compression spring acting on the gage carrier to urge it upwardly against the toggle, said spring yielding and the table, shaft and carrier, moving downwardly independently of the toggle on the exertion of excessive stress by the machine on the table.

5. In a machine of the character described, a work support slidable in the frame, an adjustable toggle secured to the frame at one end and loosely engaging the support at its other end, and a spring urging the support into engagement with the last-mentioned end of the toggle whereby movement of said end of the toggle adjusts the position of the support.

6. Yieldable means for adjusting the height of a work support including a toggle fixed at one end and having its other end adjustable, and a spring urging the support into engagement with said other end of the toggle.

7. In a machine of the character described, a work support, a toggle having one end fixed and having the other end movable, an adjusting screw for the toggle to move the movable end, an extension on the support, and yieldable means for urging the extension into engagement with the movable end of the toggle.

8. In a machine of the character described, a work support, means including a toggle fixed at one end, and movable at its other end for adjusting the height of the support, and a spring fixed at one end, and having its other

end engaging the support and movable therewith.

9. In a machine of the character described, means for supporting an article of work, 5 means for adjusting the effective height of the supporting means to receive an article of predetermined thickness for operation upon the article including a toggle, and yieldable means independent of the toggle for maintaining the supporting means in adjusted position, and yielding with said supporting means when an article of greater thickness is placed on the supporting means, and operated upon by the machine.
10. In a machine of the character described, a work support, a toggle engaging said support for adjusting the effective height of said support, and yieldable means for normally maintaining the support in its adjusted position.
11. In a machine of the character described, a frame, a work support slidable in the frame, a toggle fixed at one end to the frame and engaging the support at its other end, said toggle being adapted to adjust the effective height of the support and a spring interposed between the support and the frame for normally maintaining the support in its adjusted position.
12. In a machine of the character described, a frame, a work support slidable in the frame, a toggle fixed at one end to the frame and engaging the support at its other end, a spring interposed between the support and the frame and means for adjusting the force exerted by the spring.
13. In a machine of the character described, a frame, a bearing on the frame, a shaft slidable in the bearing, a work support 40 at the upper end of the shaft, a spring engaging member at the lower end of the shaft, a toggle connection interposed between the bearing and the spring engaging member, a spring interposed between the frame and said member, and means for adjusting the force exerted by the spring.
14. In a machine of the character described, a frame, an upright bearing on the frame, a shaft slidable in the bearing, a work support 45 removably secured to the upper end of the shaft, a spring engaging member at the lower end of the shaft, a four-arm toggle having its two upper arms hinged together and pivoted to the bearing, and having its two lower arms pivoted together and removably engaging the spring engaging member, threaded means for pivoting the respective lower ends of the upper arms to the upper ends of the lower arms, an adjusting screw passing through said threaded means for varying the distance between the upper and lower ends of the toggle, an extension on said frame, a spring interposed between said extension and the spring 55 engaging member, and means for adjusting the force exerted by said spring.
15. In a machine of the character described, a frame, an upright bearing on the frame, a shaft slidable in the bearing, a work support 60 removably secured to the upper end of the shaft, a spring engaging member at the lower end of the shaft, a four-arm toggle having its two upper arms hinged together and pivoted to the bearing, and having its two lower arms pivoted together and removably engaging the spring engaging member, threaded means for pivoting the respective lower ends of the upper arms to the upper ends of the lower arms, an adjusting screw passing through said threaded means for varying the distance between the upper and lower ends of the toggle, an extension on said frame, a spring interposed between said extension and the spring 65 engaging member, and means for adjusting the force exerted by said spring.
